UNITED STATES PATENT OFFICE.

JOSEPH L. HERZOG, OF NEW YORK, N. Y.

METHOD OF FORMING ONE-PIECE CUFF-BUTTONS.

1,148,317.

Specification of Letters Patent. Patented July 27, 1915.

Application filed November 10, 1914. Serial No. 871,288.

To all whom it may concern:

Be it known that I, JOSEPH L. HERZOG, a citizen of the United States, and a resident of New York, borough of Manhattan, in the county of New York and State of New York, have made and invented certain new and useful Improvements in Methods of Forming One-Piece Cuff-Buttons, of which the following is a specification.

10 My invention relates to a method of forming cuff buttons, the object being to devise a method for forming a cuff button of a single piece of material and wherein any of the metals may be utilized, such for instance 15 as gold, silver, filled gold, etc., the finished article, in all material respects, resembling the ordinary link button, that is a button comprising two disks with a comparatively thick post joining them together, the post 20 being bent or curved in its length in order that the disks may set at the proper angle with relation to each other, it being understood that the word "disks" is used in its broad sense and includes relatively thin 25 members of square, oval and other configurations as well as circular.

With these and other ends in view the invention consists in a method comprising various steps or operations, hereinafter fully 30 described and pointed out in the claims.

In the accompanying drawings, Figure 1 is a view in perspective of the metal plate from which the article is constructed. Fig. 2 is a view in plan of the blank as cut from the metal plate. Fig. 3 is a similar view of the partially formed button after the blank of Fig. 2 has received its first operation. Fig. 4 is an end view of the partially formed button illustrated in Fig. 3. Fig. 5 is a sectional view taken on the line 5—5 of Fig. 3, looking in the direction as indicated by the arrow. Fig. 6 is a sectional view of the partially formed button taken on the line 6—6 of Fig. 3. Fig. 7 is a plan view of the button in its next stage of formation, and Fig. 8 a sectional view taken on the line 8—8 thereof. Fig. 9 is a plan view of the button after the next succeeding operation, and Fig. 10 is a sectional view on the line 10—10 thereof. Fig. 11 is a bottom plan view of the button in its next stage of formation. Fig. 12 is a sectional view taken on the line 12—12 of Fig. 11. Fig. 13 is a view of the finished article in side elevation. Fig. 14 is a sectional view of the finished button taken on the line 14—14 of Fig. 13. Fig.

15 is a sectional view of the button shown in Figs. 11 and 12, but having the edges of the disks thickened instead of curled. Fig. 16 is a view of the button showing the post 60 merging into the disks entirely within the edges of the latter.

In constructing my improved button I make use of a flat plate of metal 20, Fig. 1, which may be of gold, silver, filled or plated 65 gold, or other desired metal or alloy, and from this plate 20, which is somewhat thicker than the disks of the finished button, yet somewhat thinner than the post of the finished button, I form by suitable cutters, (not shown) the blank 21 comprising the disk 22, the disk 23, and the connecting plate 24. This blank is then subjected to the action of suitable dies, and tools, (not shown) resulting in the partially formed 75 button as illustrated in Figs. 3, 4 and 5, the disks 22 and 23 being so compressed as to be enlarged as illustrated at 25 and 26, but materially reduced in thickness, the metal of the blank being caused to flow in 80 such a way that the connecting plate 24 is converted into a partially formed post 27, Figs. 3, 4 and 5, the metal of the partially formed post extending upwardly or outwardly from one side or surface of the two 85 disks, a part or portion of the metal constituting the disks 22 and 23 of the blank 21, flowing in such a way or manner as to cause the post to extend from the edges of the disks 25 and 26 inwardly toward the center's 90 of the latter. By the next operation the disks are cupped as clearly illustrated at 30 and 31 in Figs. 7 and 8, the edges of the disks being then trimmed as illustrated at 32 and 33 in Figs. 9 and 10. If the button 95 be made of filled gold the extreme edges of the two disks are then curled or rolled over as illustrated at 34 and 35, Fig. 12, in order to avoid the exposure of the raw edges thereof. If, however, the article is made from 100 solid metal, as for instance, solid gold, the extreme edges of the two disks may be thickened or otherwise finished as illustrated at 36 and 37, Fig. 15, or, if desired, curled or 105 rolled as illustrated in Fig. 12. In order to complete the button the post or bar 38, (Fig. 13), is then bent or curved in its length in order that the two disks 39 and 40, may be inclined, or set at the proper angle, with relation to each other. As a result of these 110 several operations a button is produced comprising the two disks 39 and 40 with finished

edges, these edges being thickened, rolled, or otherwise finished, throughout the entire periphery of the disks with the possible exception of that portion of the edge, or periphery, from which extends the post 38, the latter, that is the post 38, by reason of the several operations before described, extending outwardly from the edge or edges of the disks and forming a part thereof, and also extending inwardly from the edge of each disk toward the center as clearly illustrated in Fig. 14; in other words, in the finished article the post 38 is materially increased in thickness with relation to the blank from which the article is made, while the two disks are materially thinner than those of the blank, the post merging into the two disks at the edges of the latter, and also merging into the disks for a considerable distance within the edges.

From the foregoing it will be understood that my improved method contemplates the production of a complete link cuff button from a single piece of metal, the original blank having plain flat surfaces or sides, the resulting button comprising two comparatively thin disks with finished edges and set at an angle to each other and connected by a bar or post of comparatively thick metal, the post merging into the disks at the edges of the latter and into the metal forming the disk for a considerable distance within the edges thereof. Should, however, it be desired that the post merge into the metal of which the disks are formed entirely within the edges of said disks, a part or portion of said post may be removed, resulting in the button as illustrated in Fig. 16. In such instance I prefer to remove the metal prior to the bending of the post, *i. e.*, at that stage of the formation of the button after the disks 32 and 33 have been properly shaped and finished, and prior to bending the post 43 in its length. This removal of the metal from one side of the post may be accomplished by cutting, milling, or otherwise.

What I claim is:—

1. The method herein described of forming one piece link cuff buttons comprising the formation of a blank having plain surfaces and consisting of two disks and a connecting plate of a uniform thickness, subsequently compressing said disks whereby to cause a portion of the metal thereof to

flow into the connecting plate to form a comparatively thick post, and finally bending said post to incline said disks at an angle to each other.

2. The method hereinbefore described of forming one piece link cuff buttons, comprising the formation of a blank having plain surfaces, and consisting of two disks and a connecting plate of a uniform thickness, subsequently compressing said disks whereby to cause a portion of the metal thereof to flow into the connecting plate to form a comparatively thick post, then finishing said disks, then removing a portion of the post whereby to cause the same to merge into the disks, and finally bending said post to incline said disks at an angle to each other.

3. The method hereinbefore described of forming a one piece link cuff button consisting in forming a blank from a single piece of metal and having two disks connected by a plate of uniform thickness, then compressing said disks to cause a portion of the metal thereof to flow into the connecting plate to form a comparatively thick post, the metal of said post being caused to merge into said disks, then curling such portions of the edges of said disks as lie outside of the said post, and finally bending said post in its length to cause said disks to extend at an angle to each other.

4. The method hereinbefore described of forming one piece link cuff buttons consisting in first forming a blank having two disks and a connecting plate of uniform thickness throughout, compressing said blank in such manner as to decrease the thickness thereof and whereby to form a thickened post extending from a considerable distance within the outer edges of said disks to and including the outer edges thereof, then completing the formation of said disks and finishing the edges thereof, and finally bending the post in its length whereby to cause the said disks to extend at an angle to each other.

Signed at New York, borough of Manhattan in the county of New York, and State of New York, this 4th day of September, 1914.

JOSEPH L. HERZOG.
